his Attorney.

UNITED STATES PATENT OFFICE.

JOHN C. HIGGINS, OF SAN DIEGO, CALIFORNIA.

HYDROCARBON BURNER.

1,404,610.

Specification of Letters Patent. Patented Jan. 24, 1922.

Application filed May 11, 1921. Serial No. 468,593.

To all whom it may concern:

Be it known that I, JOHN C. HIGGINS, a citizen of the United States, residing at San Diego, in the county of San Diego and State 5 of California, have invented a certain new and useful Improvement in Hydrocarbon Burners, of which the following is a specification.

My invention relates to improvements in 10 hydro-carbon burners, adapted for burning different kinds of oil and gas.

It is particularly well adapted for burning crude oil.

The object of my invention is to provide a 15 novel burner of the kind described, which is simple, cheap to make, durable, not liable to get out of order, and which is efficient in operation.

The novel features of my invention are 20 hereinafter fully described and claimed.

In the accompanying drawing, which illustrates the preferred embodiment of my invention,

Fig. 1 is an elevation of my improved 25 burner.

Fig. 2 is a vertical sectional view on the line 2—2 of Fig. 1.

Fig. 3 is a top view of the burner.

Fig. 4 is a bottom view of the core.

Similar reference characters designate 30 similar parts in the different views.

1 designates the hollow body of the burner, the body having a flaring discharge end, and having adjacent to its other end an inlet 2 35 for air and an inlet 3 for fuel, which may be conveyed into the burner by means of a pipe 4, connected with a suitable source of supply, not shown. The inner end of the pipe 4 is upwardly turned and is provided with a discharge tip 5, which discharges through the longitudinal center of the body.

Mounted in the discharge end of the body 1 is a core, preferably hollow, comprising a cup-shaped member 6, having flaring outer 45 walls encircled by and spaced apart from the inner flaring wall 7 of the discharge end of the body.

The cup-shaped member 6 is provided on its outer flaring wall with spaced apart substantially longitudinal spiral ribs 8, disposed at an angle to the axis of the body and engaging and supported by the inner flaring wall 7 of the body.

Mounted on the cup-shaped member 6 and 55 closing the upper end thereof is provided a

cover 9, which preferably has a convex upper side.

The intake end of the body is preferably downwardly flaring, as shown, so as to afford a stable support for the body, and so as to afford ample space for the admission of the air required for combustion of the fuel.

There may be revolvably mounted in the usual manner on the flaring lower end of the body 1, a flaring ring 10, which serves as a 65 draft damper for covering or uncovering the air inlet openings 2 of the body 1.

In the operation of the burner, the fuel discharged from the tip 5 mixes with air in the body 1 and passes upwardly between the 70 ribs 8 by which the mixture has imparted to it a whirling movement which aids greatly in the intermingling of the air with the fuel, so as to obtain a maximum of efficiency.

By employing a hollow core, much weight 75 is dispensed with, and a consequent large absorption of heat by the core is avoided. By providing a cover for the cup shaped core member 6, an eddy in the mixture, which otherwise would be formed in the core is 80 avoided, and water or residue can not collect in the cup shaped member.

For limiting the movement of the damper 10, it is provided with a horizontal slot 11 through which extends a screw 12 which is 85 mounted in the body 1. If desired, the screw and slot may be dispensed with, in which case all the parts will be assembled in operative relationship without the use of screws, rivets or other accessory fastening devices. 90

I do not limit my invention to the structure shown and described, as many modifications, within the scope of the appended claims, may be made without departing from the spirit of my invention.

What I claim is:—

1. In a burner of the kind described, a tubular body having a flaring discharge end, and having adjacent to its other end an inlet for air and an inlet for fuel, and a core in 100 said discharge end having flaring outer walls spaced apart from the inner flaring wall of the body and having spaced apart longitudinal ribs engaging the flaring inner wall of the body, the ribs being disposed at an angle 105 to the axis of the body, substantially as set forth.

2. In a burner of the kind described, a tubular body having a flaring discharge end, and having adjacent to its other end an inlet 110

for air and an inlet for fuel, and a hollow core in said discharge end having flaring outer walls spaced apart from the inner flaring wall of the body and having spaced apart 5 longitudinal ribs engaging the flaring inner wall of the body, the ribs being disposed at an angle to the axis of the body, substantially as set forth.

3. In a burner of the kind described, a 10 tubular body having a flaring discharge end, and having adjacent to its other end an inlet for air and an inlet for fuel, and a cup-shaped core having flaring outer walls spaced apart from the inner flaring wall of the body 15 and having spaced apart longitudinal ribs engaging the flaring inner wall of the body, the core having a cover, substantially as set forth.

4. In a burner of the kind described, a 20 tubular body having a flaring discharge end, and having adjacent to its other end an inlet

for air and an inlet for fuel, and a hollow cup-shaped core having flaring outer walls spaced apart from the inner flaring wall of the body and having spaced apart substantially longitudinal ribs disposed at an angle 25 to the axis of the body and engaging the flaring inner wall of the body, the core having a cover, substantially as set forth.

5. In a burner of the kind described, a 30 tubular body having a flaring discharge end having adjacent to its other end an inlet for air and an inlet for fuel, and a cup-shaped core having flaring outer walls spaced apart from the inner flaring wall of the body, and 35 having spaced apart substantially longitudinal spiral ribs engaging the flaring inner wall of the body, substantially as set forth.

In testimony whereof I have signed my name to this specification.

JOHN C. HIGGINS.
